UNITED STATES PATENT OFFICE.

JOHN A. BRILL, OF PHILADELPHIA, PENNSYLVANIA.

DESIGN FOR AN UPPER CHORD FOR CAR-TRUCKS.

SPECIFICATION forming part of Design No. 22,471, dated May 23, 1893.

Application filed February 4, 1893. Serial No. 461,070. Term of patent 14 years.

To all whom it may concern:

Be it known that I, JOHN A. BRILL, a citizen of the United States, residing at Philadelphia, in the county of Philadelphia and State of Pennsylvania, have invented and produced a new and original Design for a Top or Upper Chord for Car-Trucks, of which the following is a specification.

Reference is had to the accompanying drawings forming part of this specification, in which—

Figure 1 is a perspective, and Fig. 2 a side elevation.

That part of the truck to which my design is applied is known as the top or upper chord upon which the car body generally rests. In Fig. 1 it will be seen that the chord is rectan-

gular in shape and comprises the longitudinal or side bars 1, and the cross uniting bars 2. Between the ends of the side bars 1 the chord is upset and provided with arched sections 3 which rise above the plane of the side bars. The union of the cross and side bars is rounded as at 4, Fig. 1.

I claim—

The design for a top or upper chord for car trucks, substantially as herein set forth.

Signed at the city of Philadelphia, county of Philadelphia, and State of Pennsylvania, this 1st day of February, 1893.

JOHN A. BRILL.
